US00D940718S

(12) **United States Design Patent** (10) **Patent No.:** **US D940,718 S**
(45) **Date of Patent:** **** Jan. 11, 2022**

(54) **STORAGE DEVICE**

(71) Applicant: **Seagate Technology LLC**, Cupertino, CA (US)

(72) Inventor: **Neil Poulton**, Paris (FR)

(73) Assignee: **SEAGATE TECHNOLOGY LLC**, Fremont, CA (US)

(**) Term: **15 Years**

(21) Appl. No.: **29/718,035**

(22) Filed: **Dec. 20, 2019**

(51) LOC (13) Cl. **14-02**

(52) U.S. Cl.

USPC **D14/435**
